H. F. WATERS

MEANS FOR CURING TIRES

Original Filed July 15, 1921

FIG. 1.

FIG. 2.

FIG. 4.

FIG. 3.

FIG. 5.

INVENTOR.
HARRY F. WATERS.

BY
ATTORNEY.

UNITED STATES PATENT OFFICE.

HARRY F. WATERS, OF DENVER, COLORADO, ASSIGNOR TO KARL C. SCHUYLER,
TRUSTEE, OF DENVER, COLORADO.

MEANS FOR CURING TIRES.

Application filed July 15, 1921, Serial No. 484,849. Renewed January 25, 1923. Serial No. 534,588.

To all whom it may concern:

Be it known that I, HARRY F. WATERS, a citizen of the United States, residing at the city and county of Denver and State of Colorado, have invented certain new and useful Improvements in Means for Curing Tires; and I do declare the following to be a full, clear, and exact description of the invention, such as will enable others skilled in the art to which it appertains to make and use the same, reference being had to the accompanying drawings, and to the characters of reference marked thereon, which form a part of this specification.

15 This invention relates to a method and means for curing tires and has for its object to dispense with the costly air bag now in use and substitute therefor a cheap bag made of paper or equivalent material.

20 The air bags used in curing tires are, as stated above, costly and deteriorate very rapidly thus adding materially to the cost of the tires, for this reason experiments have been conducted for the purpose of 25 eliminating them entirely but so far as I am aware, with the exception of the method outlined in my copending application Serial No. 482,501, filed July 5, 1921, they have all resulted in failures and have been abandoned.

In my present invention I do not aim to dispense with the air bag but rather to provide a bag of such material as paper or the like which is cheap and in which the deterioration will amount to only a small fraction per tire of the amount when the ordinary curing bag is used.

In order to more clearly describe my invention I shall have reference to the attached 40 drawing in which—

Fig. 1 is a cross section in which one form of my invention is shown.

Fig. 2 shows a cross section of a modified form.

45 Fig. 3 shows a fragmentary longitudinal section of the tube shown in Fig. 4.

Fig. 4 shows a cross section taken on line 4—4, Fig. 3, and

50 Fig. 5 shows a longitudinal section of a tube provided with means to permit of longitudinal expansion.

The same reference characters indicate the same parts throughout the different views.

55 In Fig. 1 I have shown a carcass 1 mounted

on the usual rim 2 and enclosed in the curing mould 3, which is made in two parts. The carcass is lined on the inside with paper 4 which extends to the inner surface of the rim 2. A flap 5, also of paper, is provided for the purpose of obtaining an air tight seal, a valve 6 being attached to paper flap 5 and extending through the rim in the manner shown. The paper must, of course, be air tight and for this purpose a paper having this property is selected or else it must be given a coating of some substance that will fill the pores and render it air tight. A fluid such as air or water is introduced into the chamber 7 and sufficient pressure applied to force the carcass into the mould after which the whole is subjected to the proper degree of heat and cured.

In Fig. 2 I have introduced within the chamber 7 a paper tube 8 provided with an air valve stem 6. The paper tube is made with two longitudinal folds 9, to allow for the requisite expansion of the tube as pressure is applied to the inner surface thereof to force the carcass against the walls of the mould. It will be noticed that when a paper tube of this type is used the rim 2 can be dispensed with and the whole enclosed in the curing moulds 4.

In Figs. 3 and 4 I have shown a paper tube 10 which is well adapted for the purpose under consideration. This tube has a part of its surface corrugated as indicated by reference numeral 11 whereby it is adapted to expand longitudinally. In order to permit it to be used in chambers of different sizes it is provided with a longitudinal lap joint 12 as clearly illustrated in Fig. 4. A valve stem 6 is provided for the introduction of the fluid. When a tube like that shown in Figs. 3 and 4 is used, the rim 2 can be dispensed with and the carcass enclosed directly within the curing moulds as shown in Fig. 2.

In Fig. 5 I have shown a modified tube 13 in which longitudinal expansion is provided for by means of an annular fold 14. This tube is used in the same manner as tubes 8 and 10. Instead of an annular fold as shown, the tube may be cut and one end inserted into the other resulting in a slip joint.

From the above it appears that I have invented a cheap tube of paper that can be used for replacing the costly air bag now

in use in curing automobile and similar tires. These tubes are cheap as to first cost and are also capable of withstanding the strain of repeated use, thus resulting in a 5 very economical device for the purpose under consideration.

Having described my invention what I claim as new and desire to have protected by Letters Patent is:

- 10 1. An air bag for use in curing tires comprising a paper tube.
2. An air bag for use in curing tires comprising a paper tube provided with means to permit it to expand to fill the chamber in 15 the tire carcass.
3. An air bag for use in curing tires comprising a paper tube, provided with means to permit it to expand longitudinally so as to fill the chamber in the tire carcass.
- 20 4. An air bag for use in curing tires comprising a paper tube, provided with means to permit it to expand longitudinally and transversely so as to fill the chamber in the tire carcass.
- 25 5. An air bag for use in curing tires comprising an annular paper tube.

6. An air bag for use in curing tires comprising an annular paper tube provided with means to permit it to expand so as to fill the chamber in the tire carcass. 30

7. An air bag for use in curing tires comprising an annular paper tube, provided with means to permit it to expand longitudinally so as to fill the chamber in the tire carcass. 35

8. An air bag for use in curing tires comprising an annular paper tube provided with means to permit it to expand longitudinally and transversely so as to completely fill the chamber in said tire carcass. 40

9. An air bag for use in curing tires comprising an annular paper tube having a longitudinal lap joint and transverse corrugations whereby it can expand both transversely and longitudinally. 45

10. A lining for use in curing tires, consisting of paper, provided with means to permit it to expand so as to fill the chamber in the tire carcass.

In testimony whereof I affix my signature.

HARRY F. WATERS.
